ELECTRICAL TAB RECEPTACLE

William Vito Pauza, Palmyra, and Wilmer Lee Sheesley, Harrisburg, Pa., assignors to AMP Incorporated, Harrisburg, Pa.

Original design application Jan. 7, 1974, Ser. No. 431,178. Divided and this application Feb. 4, 1975, Ser. No. 546,961

Term of patent 14 years

Int. Cl. D13—03

U.S. Cl. D26—1 A

FIG. 1

FIG. 2

FIG. 3

FIG. 4

FIG. 5

FIG. 1 is a top plan view of an electrical tab receptacle showing our new design;

FIG. 2 is a side elevational view thereof;

FIG. 3 is a front elevational view thereof;

FIG. 4 is a rear elevational view thereof; and

FIG. 5 is a bottom elevation view thereof.

This is a division of application Ser. No. 431,178, filed Jan. 7, 1974.

We claim:

The ornamental design for an electrical tab receptacle, as shown.
